US00D975969S

(12) **United States Design Patent** (10) Patent No.: **US D975,969 S**
(45) Date of Patent: **** Jan. 24, 2023**

(54) **SHOE**

(71) Applicant: **Specialized Bicycle Components, Inc.**,
Morgan Hill, CA (US)

(72) Inventors: **Robert Arthur Laurence Cook**,
Bayern, DE (US); **Stephen Randall Quay**, San Jose, CA (US); **Ashley Gill Sult**, Santa Clara, CA (US); **Nicholas Reid Gosseen**, Seattle, WA (US)

(73) Assignee: **Specialized Bicycle Components, Inc.**,
Morgan Hill, CA (US)

(**) Term: **15 Years**

(21) Appl. No.: **29/756,877**

(22) Filed: **Oct. 30, 2020**

Related U.S. Application Data

(63) Continuation-in-part of application No. 29/756,340, filed on Oct. 27, 2020.

(51) **LOC (14) Cl.** **02-04**

(52) **U.S. Cl.**

USPC **D2/908**; D2/902; D2/907

(74) *Attorney, Agent, or Firm* — Knobbe, Martens, Olson & Bear, LLP

(57) **CLAIM**

The ornamental design for a shoe, as shown and described.

DESCRIPTION

FIG. 1 is a front and left side perspective view of a shoe showing our new design;

FIG. 2 is a left side view thereof;

FIG. 3 is a right side view thereof;

FIG. 4 is a top view thereof; and,

FIG. 5 is a bottom view thereof.

Even dashed broken lines are used to illustrate features of the shoe which form no part of the claimed design. Dot-dot-dashed broken lines are used to illustrate stitching which forms no part of the claimed design.

1 Claim, 5 Drawing Sheets
